UNITED STATES PATENT OFFICE.

FREDERICK YUNCK, OF BRYAN, OHIO.

DESIGN FOR A BICYCLE PARCEL-CARRIER.

SPECIFICATION forming part of Design No. 26,795, dated March 23, 1897.

Application filed February 3, 1897. Serial No. 621,889. Term of patent 7 years.

To all whom it may concern:

Be it known that I, FREDERICK YUNCK, a citizen of the United States, residing at Bryan, in the county of Williams and State of Ohio, have invented and produced a certain new and original Design for Bicycle Parcel-Carriers; and I do declare the following to be a full, clear, and exact description of the invention, such as will enable others skilled in the art to which it appertains to make and use the same.

My invention relates to a design for a parcel-carrier for bicycles.

It relates to the entire configuration of the parcel-carrier, and especially to a parcel-carrier formed of spring-wire.

My invention relates particularly to a parcel-carrier as illustrated in the accompanying drawing, in which the figure is a perspective view of a bicycle parcel-carrier embodying my design.

The leading features of my design appear in the following description:

1 represents the semicircular yoke, formed with approximately circular parallel jaws 2 2, which project downwardly to form loops 3 3, 25 the free ends of which are turned upwardly and curved outwardly to form hooks 4 4 with looped ends 5 5.

Having thus fully described my design, what I claim as new, and desire to secure by 30 Letters Patent of the United States, is—

The design for a bicycle parcel-carrier, substantially as herein shown and described.

In testimony whereof I hereunto affix my signature in presence of two witnesses.

FREDERICK YUNCK.
